UNITED STATES PATENT OFFICE

GEORGE H. MAGRATH, OF WHITINSVILLE, MASSACHUSETTS

BOBBIN CLUTCH

Application filed September 11, 1930. Serial No. 481,113.

This invention pertains to that type of spindles commonly employed in spinning or other textile operations, and more particularly relates to an improved bobbin clutch having expansible clutching members which maintain the bobbin in position during the spinning or other operation.

It is the object of this invention to provide a bobbin clutch which is of simple construction, economical to manufacture and easy to assemble, which is efficient and durable in use, and which is generally superior to bobbin clutches now or heretofore in use. Further objects and advantages will be apparent as attributes of the novel construction and operation herein shown and described.

For the purposes of illustration one concrete embodiment is shown in the accompanying drawings, wherein:

20 Fig. 1 is an elevation, partly in section, of a bobbin clutch exemplifying a preferred form of the invention;

Fig. 2 is a plan view of the cap;

Fig. 3 is a view of the blank from which 25 an element constituting a part of the spring is made;

Fig. 4 is an elevation of a part of the spring mechanism constructed from a blank shown in Fig. 3;

30 Fig. 5 is a plan view and elevation of the ferrule; and

Fig. 6 is a side and rear elevation of a contact segment.

The particular embodiment of the invention chosen for the purpose of illustration comprises an ordinary blade 1 and a whirl 2 fixedly mounted on the blade by a pressed fit, the whirl 2 having a hub 3 from which projects an annular neck 4. The cap 5 is fitted on the hub 3 with its cylindrical wall 6 frictionally engaging the periphery of the hub. The top of the cap 7 is provided with a circular opening 8 concentric the blade (when in the assembled relation shown in 45 Fig. 1) which with neck 4 defines an annular recess 9 concentric the blade. The end 7 of the cap also serves as a bobbin seat. About the circumference of the opening 8 is a plurality of similar, circumferentially spaced recesses 10 adjoining the circular opening 8.

Mounted on the blade 1 in opposition to the hub 3 is a case concentric the blade and having a plurality of similar, symmetrically disposed, circumferentially separated fingers 12 projecting from its head 11 into the annular recess 9 with ends adjacent to or engaging the rim of the circular opening or annular recess 9 intermediate the recesses 10. Disposed in the slots intermediate the fingers 12 are a plurality of elongate contact pieces 13 having their lipped ends 14 engaging interiorly the case, and their hooked ends 15 projecting into the recesses 10 adjoining the annular recess 9.

The spring 16 is preferably a two-piece structure, both pieces being of the same construction and similar in all respects, each having an annular portion or base 17 and a plurality of similar, symmetrically disposed, circumferentially separated fingers 18. The outer diameter of the annular portion 17 is preferably approximately equal to the inner diameter of the case, and the inner diameter of the annular portion 17 is preferably equal to that of the blade, thus insuring a close fit between the respective parts. The base or annular portion 18 of one is superposed on the base of another so that their corresponding surfaces engage and the fingers project in opposite directions as shown in the assembled mechanism in Fig. 1. The assembled spring element thus defines an annular member from which two similar, divergent fingers project in opposite directions along the blade.

The spring 16 having its annular members 17 snugly fitting the blade 1 and concentric therewith at a point in a plane passing through the contact pieces approximately midway between their ends is secured in position by means of the ferrule 19 which abuts the neck 4 and the ferrule 20 which has a pressed fit on the blade 1. Both ferrules frictionally engage the respective annular members 17 of the spring and preferably have a pressed fit on the blade, thus preventing any movement of the spring either radially or longitudinally of the blade.

Each of the divergent fingers engage the same contact piece on opposite sides of a point

approximately midway between the ends of its bobbin-engaging surface, as shown in the assembled construction in Fig. 1.

In assembling the parts the whirl 2 is first applied to the blade 1 and the ferrule 19 is then applied over the blade and seated on the neck 4. The portion of the spring with fingers projecting toward the whirl is next applied over the blade and positioned so that its annular portion is seated on ferrule 19. The portion of the spring with its fingers projecting toward the case is similarly applied and arranged so that its projecting fingers are in vertical alignment relative to the blade 15 with the corresponding fingers of the lower portion. The ferrule 20 is then pressed on over the blade with one end seated on and frictionally engaging the annular member 17 and causing a frictional engagement between both members 17 of the spring and the ferrule 20, thus preventing both radial and longitudinal movement of the spring relative to the blade. Preferably at this time, the cap 5 is applied over the blade and pressed 25 on the hub 3 so that the recesses 10 of the circular opening 8 are in radial alignment relative to the blade with the fingers 18 of the spring. The case is pressed partially on the blade and the contact pieces are inserted 30 in the slots between the fingers 12, and while being so held, the case is pressed into position with the ends of its fingers 12 extending into the annular recess 9 and engaging the portion of the rim of the cap 5 intermediate the recesses 10. When thus assembled the contact pieces are in radial alignment, relative to the blade, with the spring fingers 17 and engaged thereby.

It is obvious that the lower ferrule 19 is used merely to maintain the annular members 17 of the spring in a spaced position from the hub and consequently it might be considered advisable to use a whirl having a hub with an annular neck of a sufficient height which would not require the use of a collar or ferrule; to the same end it would be quite possible to use a whirl having a hub without a neck and using a ferrule of sufficient height to maintain the proper spaced position of the annular member 17. Any such modification of structure would not alter the functional character or relation of the constituent elements of the mechanism.

From the foregoing it will be seen that the outward movement of the contact segments is limited by the ends 14 and 15 abutting, respectively, the interior of the case and the portions of the cap opposite the openings of the recesses 10. This construction does not limit the contact pieces to a pivotal or rocking movement about either of their ends, but permits a parallel movement relative to the blade of the entire piece. This design is particularly advantageous in that the contact pieces are capable of yielding so as to

engage bobbins having tapering and uniform bores as well as those having uniform bores. Since each of the contact pieces is engaged by two of the spring fingers pressing outwardly on each piece with approximately equal pressure, each of the contact pieces will press more firmly against the bore of the bobbin and thus hold it more securely in place.

In the preferred construction, the contact pieces fit snugly in the slots between the case fingers, and the latter engage in a similar manner the rim of the circular opening 8 of the cap and thus prevent any dirt, lint, etc., from entering to any substantial extent the interior of the case, thereby offering a protection which will insure an unimpaired operation.

It should be understood that the present disclosure is for the purpose of illustration only and that this invention includes all modifications and equivalents which fall within the scope of the appended claims.

I claim:

1. A device of the character described comprising a blade, a whirl on the blade, a case on the blade having a head in spaced relation to the whirl and having longitudinal slots intermediate the head and whirl, elongate contact pieces movable in said slots for engaging the interior of a bobbin, and spring means pressing outwardly on each piece with approximately equal pressure on opposite sides of a point approximately midway between the ends of its bobbin-engaging surface.

2. An apparatus of the character described comprising a blade, a whirl secured to the blade, a case concentric the blade and secured at its head thereto and having a plurality of elongate slots, a plurality of contact pieces disposed in the slots of the case, and a spring having resilient fingers projecting in opposite directions toward the whirl and head, respectively, and engaging said contact pieces on opposite sides of a point approximately midway between the ends of the bobbin-engaging surface.

3. Apparatus of the character described comprising a blade, a whirl secured to the blade, the whirl having a hub provided with an annular recess concentric the blade, a case mounted on the blade and having spaced fingers extending into said recess, bobbin contact pieces disposed between said fingers and extending into said recess, and a spring having fingers engaging the contact pieces on opposite sides of a point approximately midway between the ends of its bobbin-engaging surface.

4. An apparatus of the character described comprising a blade, a whirl secured to the blade, a case secured to the blade having a head in spaced relation to the whirl, and resilient means for frictionally engaging a

- bobbin, said means comprising an annular member concentric the blade and secured in a spaced position relative to the whirl and having resilient fingers diverging in opposite directions toward the whirl and head, respectively, and means for maintaining said annular member in spaced position relative to the whirl.
5. An apparatus of the character described comprising a blade, a whirl secured to the blade, a case concentric the blade and secured thereto and having a plurality of elongate slots, a plurality of contact pieces disposed in the slots of the case, and resilient means 10 engaging said contact pieces, said means comprising an annular member concentric the blade at a point in a plane approximately midway between the ends of the bobbin-engaging surfaces of said contact segments and having resilient fingers urging each contact segment outwardly against the bobbin with approximately uniform pressure throughout the length of the bobbin-engaging surfaces.
15. 6. Apparatus of the character described comprising a blade, a whirl secured to the blade, the whirl having a hub provided with an annular recess concentric the blade, a case mounted on the blade and having spaced fingers 20 extending into said recess, bobbin contact pieces disposed between said fingers and extending into said recess, and a spring having fingers engaging the contact pieces on opposite sides of a point approximately midway between the ends of its bobbin-engaging surface, said spring urging each contact piece outwardly against the bobbin with approximately uniform pressure throughout the length of the bobbin-engaging surface.
25. 7. An apparatus of the character described comprising a blade, a whirl secured to the blade, a cap fitting the hub and having a circular opening concentric the blade and defining therewith an annular recess, a case mounted 30 on the blade and having a plurality of spaced fingers extending into the annular recess, a plurality of contact pieces disposed between the case fingers and having their ends extending into the annular recess, and a spring having an annular member concentric the blade and a plurality of resilient fingers projecting in opposite directions and engaging each contact piece on opposite sides of a point approximately midway between the ends of its bobbin-engaging surface.
35. 8. An apparatus of the character described, comprising a blade, a whirl secured to the blade, the whirl having a hub provided with a neck concentric the blade, a cap fitting the hub and having a circular opening concentric the blade and a plurality of circumferentially spaced recesses adjoining said opening, the cap and the blade defining an annular recess, a case mounted on the blade and having a plurality of spaced fingers ex-
- tending into the annular recess intermediate said adjoining recesses, a plurality of contact pieces disposed between the case fingers and having their lower ends extending into the recesses adjoining said annular recess, a 40 spring comprising an annular member concentric the blade and having a plurality of divergent resilient fingers projecting in opposite directions and pressing outwardly on each contact piece with approximately equal pressure on opposite sides of a point approximately midway between the ends of its bobbin-engaging surface, and means maintaining said annular members in a spaced position relative to the neck and preventing radial and longitudinal movement relative to the blade.
